UNITED STATES PATENT OFFICE.

BENJAMIN DAY CHAMBERLIN, OF CORNING, NEW YORK, ASSIGNOR TO EMPIRE MACHINE COMPANY, OF PORTLAND, MAINE, A CORPORATION OF MAINE.

MOLD MECHANISM FOR GLASS-BLOWING MACHINES.

1,156,056.

Specification of Letters Patent.

Patented Oct. 12, 1915.

Original application filed March 23, 1910, Serial No. 551,198. Divided and this application filed August 24, 1912. Serial No. 716,916.

To all whom it may concern:

Be it known that I, BENJAMIN D. CHAMBERLIN, a citizen of the United States of America, and a resident of Corning, county 5 of Steuben, and State of New York, have invented certain new and useful Improvements in Mold Mechanisms for Glass-Blowing Machines, of which the following is a specification.

10 This application, which is a division of my prior application, Serial Number 551,198, filed March 23, 1910, for improvements in the production of glass articles, relates to a new and improved mold mechanism for glass blowing machines, and especially to the means for closing the mold through a yielding connection, whereby breakage of the molds is prevented if their full closing is obstructed and whereby the 15 molds are opened at proper times, and for these purposes my invention consists in the construction, arrangement and combination of the several parts of which it is composed, as will be hereinafter more fully described 20 and claimed.

Referring to the accompanying drawings in which corresponding parts are designated by corresponding marks of reference: Figure 1 is a vertical transverse section 30 through the base of a glass blowing machine, to which my improved mold is applied. Fig. 2 is a horizontal section on line x^2-x^2 thereof. Fig. 3 is a detail of the mold dipping mechanism. Fig. 4 is a perspective view of the mold mechanism. Fig. 5 is an inverted plan view thereof. Fig. 6 is a detached perspective view of certain parts thereof.

The type of machine, to which my improved mold is shown as applied comprises a suitable base 1, having a vertical tubular standard 2 arising from the top thereof, these parts serving as guides and bearings for a sleeve 3, having rigidly attached to its lower end a mold supporting spider 4, and to its upper end proper devices for holding and positioning a blow-pipe 22, as is fully described and shown in my original application before referred to.

50 While the base 1 is by preference mounted on wheels, as shown, the term "stationary" is applicable thereto (in that in the operation of the machine it has no movement) in contradistinction to the spider 4, which

in operation revolves around the vertical 55 axis formed by the standard 2.

The weight of sleeve 3 and the parts carried thereon is supported on a thrust bearing consisting of balls 3^a contained in an annular groove in the bottom of the sleeve 3, 60 and in a corresponding groove in the upper face of a shoulder 1^a surrounding the base of the standard 2, the sleeve being guided by machined faces 2^b on the standard which co-operate with corresponding faces on the 65 sleeve.

The sleeve has attached to its lower end a beveled annular gear 3^b surrounding the lower end of the standard and meshing with a beveled pinion 6 (Fig. 2) contained in a 70 pocket 1^b in the base 1 and mounted on a horizontal shaft 6^a driven through reducing gearing 6^c by a suitable motor 6^b, supported on an extension 1^e of the frame 1. In this manner the sleeve and parts thereon are 75 caused to revolve around the standard as a center with an angular velocity determined by the speed of the motor, which should be adjusted to cause the proper functioning of the machine as will be hereinafter described. The spider 4 fast on the lower end of the sleeve 3 comprises a central hub 4^a and a series of radial arms 4^b (shown as 80 eight in number).

Each of the spider arms 4^b is radially 85 bored to form a bearing for a tubular shaft 38 rotatable therein, such shaft terminating beyond the arm in a cross head 38^a, to the one end of which cross head (the forward end) the two halves of a separable mold 39 90 are pivoted by their ears 39^a and 39^b respectively and the pivot bolt 39^c. A gear 40 is formed upon the tubular shaft and is in mesh with the rack 40^a sliding in an inclined guide 40^b in the spider arm, the lower 95 end of the rack being inclined forwardly and carrying a roller 40^c running upon the crown of a concentric cam track 40^d formed upon or attached to the base 1, so that in the rotation of the spider with the sleeve 3, 100 the roller running upon the cam track will so shift the rack as to reciprocatingly rotate the tubular shaft and will impart such motion to the mold parts carried by the outer end thereof as will cause them to hang 105 below the tubular shaft with the axes of their mold cavities horizontal or will cause them to swing upwardly and assume a po-

sition in which the axes of their mold cavities will be vertical.

Within the tubular shaft 38 is contained the rotatable horizontally reciprocating shaft 41 having fast upon its inner end a collar 41^m having separable flanges 41ⁿ and 41°, in the channel between which is rotatably mounted a disk 41^p which has on one part of its periphery a stud roller 41^q which 10 is located in a cam track 44 in an annular casting 44^a mounted upon the base 1. Rotation of the disk 41^p is prevented by the bifurcated extension 41^r upon the disk, which extension straddles the web of the arm 4^b of the spider, thus holding the roller 41^q in the cam track. The outer end of the shaft 41 which projects beyond the tubular shaft 38 carries a cross head 41^a slidably mounted thereon and normally held at its outer limit 15 of movement against the set nuts 41^b by a spiral spring 41^c interposed between it and a washer 41^d mounted upon the shaft 41. One end of the cross head 41^a is connected by a link 42 with the rearward extension of 20 one of the ears 39^b of one part of the mold and the other end of the cross head is connected by a link 43 with one end of a bell crank lever 43^a pivoted to the rearward extension of the cross head 38^a on the tubular 25 shaft 38, the other end of such lever being connected by a link 43^b with one of the ears 39^c of the other half of the mold, so that when the reciprocating shaft 41 is by the cam track 44 projected outwardly such 30 movement will be communicated to the link 42 and directly swing inwardly half of the mold on the pivot bolt 39^e to close and will through the link 43, bell crank 43^a and link 43^b be also transmitted to the other half of 35 the mold to throw it outwardly upon the pivot bolt to close. The terms "outwardly" and "inwardly" here used have reference to the movement of the mold parts as measured from the vertical axis of the machine. The 40 shape of the cam 44 is such that the molds are opened at all times when the axes of their central mold cavities are horizontal and are closed and reopened when the molds have been so swung that the axes of such 45 cavities are vertical.

A cooling tank 45 is attached to the side of the base and extends in an arc of a circle on that side thereof at which the molds are lowered and raised, so that when properly 50 filled with water, the molds will travel therethrough to be wetted.

In the operation of my device in the machine shown, the travel of the mold mechanisms in respect to the fixed base and cam

tracks mounted thereon results in a lowering of the mold parts into the tank 45 by the cam track 40^d to cool them; and in a lifting of the molds by the same track; in a closing of the mold parts by the cam track 44 on a gather, the gather being positioned by a blow-pipe and after a proper time to permit the formation of the blown articles, by an opening of the mold parts taking place while they are lifted. 70

Inasmuch as this application has been filed in response to a requirement from the Office as a division of my aforesaid original application, No. 551,198 to contain claims upon the mold-actuating mechanism, the 75 claims hereof are so restricted, and I reserve right to make claims to other features which may be shown herein in my aforesaid original application.

Having thus described my invention what 80 I claim is:—

1. In a glass molding machine, the combination with a rotary tubular shaft having separable mold parts carried thereby, a shaft reciprocating within the tubular 85 shaft and connected to the mold halves to close the same, means to rotate the tubular shaft to lift the mold, and means constantly controlling the position of the shaft within the tubular shaft and to reciprocate the 90 same therein to close and open the mold.

2. In a glass molding machine, the combination with a cam track, of a rotary tubular shaft movable angularly thereover, mold parts carried by the shaft, a shaft reciprocating within the tubular shaft, and connected to the mold halves to close the same, and a member mounted on the reciprocating shaft and having a constant engagement with the cam, to control the movements of 95 the former. 100

3. In a glass-blowing machine, the combination with a rotary tubular shaft, of separable mold parts carried to one side of the axis thereof, of a shaft reciprocating within 105 the tubular shaft and connected to the mold parts to close the same, means to rotate the tubular shaft to lift the mold, and means constantly controlling the position of the shaft within the tubular shaft, and to reciprocate the same therein to close and open the mold parts. 110

In testimony whereof I have signed my name in presence of two witnesses.

BENJAMIN DAY CHAMBERLIN.
